LIQUID PUMP FOR THE PURPOSE OF SPINNING MILLS

Filed July 22, 1927

Inventor:
Paul Knappe

UNITED STATES PATENT OFFICE

PAUL KNAPPE, OF CHEMNITZ, GERMANY, ASSIGNOR TO FIRM: GEBRÜDER LUDWIG MASCHINENFABRIK, OF GRUNA I SA, GERMANY

LIQUID PUMP FOR THE PURPOSE OF SPINNING MILLS

Application filed July 22, 1927, Serial No. 207,804, and in Germany July 28, 1928.

Liquid pumps with disk like eccentrically working pressure elements have become known in which the inflow and outflow channels for the liquid are separated by a slide 5 valve connected to the pressure element. Said slide is either guided in a rotatably mounted disk or pressed upon the periphery of the disk-like pressure element by the action of a spring. It has further been proposed to mount several 10 such individually driven pressure elements, the one behind the other.

The present invention relates to a liquid pump which is mainly designed to serve for the purpose of spinning mills. As is well 15 known the main condition in this case is not only that each pump work permanently uniformly, but also that all pumps mounted on the same machine possess accurately the same efficiency. Heretofore this could be attained 20 neither with the piston pumps nor with the gear driven pumps commonly used for this purpose which are exposed to comparatively rapid wear. Specially those types of pumps 25 did not serve for this purpose, the pressure elements of which were driven independently from each other.

The characteristic feature of my present invention consists therein that on one and the same driving shaft at least two eccentrically working pressure elements, connected 30 to a controlling slide valve movable like a pendulum, are mounted in such a manner that the working periods of the several pressure elements succeed one another. If for instance 35 two such elements are mounted on a common shaft, it is expedient to displace 180° the eccentric rings which control said elements. The advantage of this arrangement consists in that the pump works absolutely free from 40 shocks so that the delivered quantity of the same is absolutely constant. This is for the purpose of spinning mills of the greatest importance as every, even the slightest, variation in its delivery influences the thickness of the 45 thread to be produced and consequently the uniformity of the fabric made from the same.

A further characteristic feature of my invention consists in that the orifices of the inflow and outflow channels for the liquid to 50 be delivered (for instance viscose) are ar-

ranged directly on the side faces of the controlling slide and open on preliminary flood spaces which are arranged in the sides of said slide. By this arrangement a good packing of the channel orifices at the moment of the reversing is ensured on the one hand and on the other hand a uniform inflow or outflow of the liquid into or from the useful space of the pump whereby also the uniformity of the function of the pump is favorably influenced. 55 As extraordinary high requirements are asked for spinning mills in relation to the exactness of their function it is of great importance that the force of friction of the rotating parts is reduced to a minimum. 60

According to a special form of construction of my invention this effect is attained in that the slide valves end in a head with circular cross-section which is arranged either in a suitable sparing of the casing or in a 70 suitable sparing of the pressure elements which head serves for said pressure elements as a pivot.

I have illustrated my invention in the accompanying drawing in which

Fig. 1 is a longitudinal section.

Fig. 2 shows an elevation of the inner arrangement viewed in the direction of the arrow C and corresponding to line A—B of Fig. 1.

The two sides of the pump operate in series.

In the form of construction shown in Figs. 1 and 2 two disk like pressure elements *c* and *c'* are mounted in the casing *A* on a common 85 working shaft *a*, said elements working in the spaces *b* and *b'* and being controlled each by one of the two eccentric elements *d* and *d'* displaced 180° the one to the other. Each of the two pressure elements *c* and *c'* is connected at *e* to a slide valve *f* and *f'* respectively, the free ends of which are guided in a rotatably mounted disk *g*, *g'* respectively. The slide valves *f* and *f'* extend through slots *h* which make the working spaces *b*, *b'* communicate with the bearing points for the disks *g*, *g'*. These slots *h* are slightly wider than the slide valves *f*, *f'* so that the latter at the eccentric rotation of the pressure elements *c*, *c'* can execute an oscillating movement. *i* is 95 100

the inflow channel and k is the outflow channel for the liquid. The orifices i^1 and k^1 of these channels are situated directly on the side faces of the control elements or slide valves f or f^1 . These slide valves have further on either side a preliminary flood space l , l^1 . The preliminary flood space l of each slide valve is filled before the liquid can flow into the working space b . The preliminary flood space l^1 is filled before the liquid enters into the outflow orifice k . The arrangement of these preliminary flood spaces increases the uniformity of the inflow of the liquid into the working spaces and of the outflow of the same from said working spaces.

15 What I claim as new and desire to secure by a United States Letters Patent is:—

In a liquid pump for the purpose of spinning mills in combination a casing, consisting of three plates connected to each other, one of the outer plates having an inflow channel, the other one having an outflow channel for the liquid, the center plate provided with a circular recess on both sides and a longitudinal recess annexed to said circular recess, a circular piston and a controlling slide valve firmly connected with said piston in said recesses, said center plate also having inflow and outflow channels for the liquid and said slide valve being positioned to separate the inflow and outflow channels, a shaft mounted in said casing and carrying two eccentric disks displaced the one with regard to the other a like distance, each eccentric disk carrying and controlling one of said circular pistons, a further circular recess on each side of said center plate and a circular guiding disk for each of said slide valves therein, all substantially as described and set forth.

40 In testimony whereof I have hereunto signed my name this 22nd day of April, 1927.

PAUL KNAPPE.
